(57) **CLAIM**

The ornamental design for a docking station, as shown and described.

DESCRIPTION

FIG. 1 is a first isometric view of a docking station in accordance with our design;

FIG. 2 is a second isometric view thereof;

FIG. 3 is a front view of the docking station of FIG. 1;

FIG. 4 is a rear view of the docking station of FIG. 1;

FIG. 5 is a first side view of the docking station of FIG. 1;

FIG. 6 is a second side view of the docking station of FIG. 1;

FIG. 7 is a top view of the docking station of FIG. 1; and,

FIG. 8 is a bottom view of the docking station of FIG. 1.

The broken lines depict portions of the docking station that form no part of the claimed design.

1 Claim, 7 Drawing Sheets
